UNITED STATES PATENT OFFICE.

FELIX LUNAR LOPEZ, OF DENBO, PENNSYLVANIA.

MECHANICAL TOY.

Application filed November 21, 1923. Serial No. 676,006.

To all whom it may concern:

Be it known that I, FELIX LUNAR LOPEZ, a subject of the King of Spain, residing at Denbo, in the county of Washington and 5 State of Pennsylvania, have invented certain new and useful Improvements in Mechanical Toys, of which the following is a specification.

This invention relates to mechanical 10 toys, having more particular reference to toys of the type in which a carriage is adapted to be moved along a surface, and by rotation of its wheels cause certain parts mounted upon the carriage to move relatively to 15 the latter, the invention having for an object the provision of a novel and inexpensive toy of this type arranged to simulate a carousel.

For further comprehension of the invention, and of the objects and advantages 20 thereof, reference will be had to the following description and accompanying drawing, and to the appended claims in which the various novel features of the invention are more particularly set forth.

Fig. 1 of the drawing is a horizontal sectional view of my improved toy, this view being taken on the line 1—1 of Fig. 2.

Fig. 2 is a side view thereof.

Fig. 3 is a transverse vertical sectional 30 view taken on the line 3—3 of Fig. 1.

Fig. 4 is a fragmentary longitudinal sectional view taken on the line 4—4 of Fig. 3.

As here embodied my improved toy comprises a carriage consisting of a double-walled platform 10 mounted on front and rear wheels 11 and 12 respectively. This carriage may have a suitable draft handle 13 attached thereto, or it may be arranged 35 for propulsion in any desired manner. Extending upward through the platform 10 and suitably journaled, as in the bearing element 15, is a vertical shaft 16 which may carry a conical hood 17 on its upper end from which a number of figures 18 are suspended, these figures being caused to move 40 around the shaft 16 as the latter rotates.

To rotate the shaft 16 I provide a fifth wheel 20 mounted on a transverse shaft 21 extending under the platform 10 and suitable supported at its ends in the side bearing elements 22. Fixed to the shaft 21 is a ratchet wheel 24 which has a one-way operative connection with a gear pinion 25 loose on the shaft 21, this operative connection being here effected by means of spring-pressed pawl 26 pivoted to the pinion 25 and

engaging the ratchet wheel 24. The gear pinion 25 meshes with a large gear 28 mounted on the lower end of the vertical shaft 16.

In connection with my improved toy I 60 preferably provide a device adapted to give a variable rotary movement to the shaft 16, and in consequence a variable rate of travel to the figures 18. To this end a smaller gear element 30 is fixed to the gear 28 and is 65 adapted to be engaged at certain times, or during a certain portion of each revolution of the shaft 16, by a gear segment 31 fixed to the horizontal shaft 21. As this gear segment 31 engages the gear element 30 it causes 70 the shaft 16 to be driven at an increased rate of rotation during the time these two parts are in engagement with one another.

I also preferably provide a means for 75 causing various musical sounds to be given forth as the shaft 16 rotates. As here shown a short cylindrical element 35 surrounds the shaft 16 just above the platform 10 and is spaced some distance from said shaft. Fixed to the platform 10, and closely surrounding 80 the member 35 is an annular wall 35' which serves as a guide for said member. Mounted on the inner face of this member 35 are a number of devices 36 adapted to give off 85 sounds when struck by a striker in the form of a crosspin 37 carried by the shaft 16. These devices are spaced around the member 35 at relatively varying heights, and to cause the order of engagement with the striker 37 to be varied, I arrange means to give the 90 cylindrical member 35 a vertical movement. To this end a forked lever 40 is connected at one end to the member 35 as indicated at 95 41, this lever being fulcrumed between its ends as at 42, and having connected to its other end a vertical link 43 which extends downward and connects at its lower end to one end of a rock lever 44 fulcrumed between its ends as at 45 under the top element of 100 the platform 10 and having its other end engaged in an irregular cam groove 46 in the periphery of a cam disk 47 to which is fixed a gear 48 meshing with a gear 49 fixed to the shaft 16, the gears 48, 49 having a variable ratio with respect to each other so that the order in which the devices 36 are 105 engaged by the striker 37 will vary with each revolution of the shaft 16.

It is believed that the manner of operation 110 of my improved toy will be readily understood from the above description, it being apparent that when the toy is moved along

a floor or other surface, the figures 18 will be caused to swing around the shaft 16 with a variable motion, while the striker 37 will engage the devices 36 and cause various musical sounds to be given off.

Having thus described my invention what I claim as new and desire to protect by Letters Patent of the United States is as follows:

- 10 1. A toy comprising a carriage, a carousel element mounted thereon, and means for giving said carousel element a variable rotary movement as the carriage is moved along a surface, said means comprising a shaft, a gear pinion having a one-way operative connection with said shaft, a pair of gears of different diameters fixed to the carousel element, said gear pinion meshing with one of said gears, and a gear segment fixed to the said shaft and meshing with the other of said gears.
- 15 2. A toy comprising a carriage, a carousel element including a vertical shaft mounted thereon, a pair of gears of different diameters fixed to the lower end of said shaft, a horizontal shaft, a gear pinion loose on said horizontal shaft and having a one-way operative connection with the latter, said gear pinion meshing with the larger of said gears, and a gear segment fixed on said horizontal shaft and adapted at times to engage the smaller of said gears, and means for rotating said horizontal shaft.
- 20 3. A toy comprising a carriage, a carousel element including a vertical shaft mounted thereon, a pair of gears of different diameters fixed to the lower end of said shaft, a horizontal shaft, a gear pinion loose on said horizontal shaft and having a one-way operative connection with the latter, said gear pinion meshing with the larger of said gears, and a gear segment fixed on said horizontal shaft and adapted at times to engage the smaller of said gears, and means for rotating said horizontal shaft, said means com-

prising a wheel fixed to said shaft and adapted to rest on the surface on which the carriage rests.

4. A toy comprising a carriage, a carousel element thereon including a vertical shaft, means for rotating said shaft, and a musical device comprising a cylindrical member surrounding and spaced from said shaft, a series of sound emitting elements on said cylindrical member, a striker on said shaft, and means for vertically oscillating said cylindrical member.

5. A toy comprising a carriage, a carousel element thereon including a vertical shaft, means for rotating said shaft, and a musical device comprising a cylindrical member surrounding and spaced from said shaft, a series of sound emitting elements on said cylindrical member, a striker on said shaft, and means for vertically oscillating said cylindrical member, said last named means comprising a lever connected to said member, a rotary cam having an operative connection with said lever, and gear connections between said cam and said vertical shaft.

6. A toy comprising a carriage, a carousel element thereon including a vertical shaft, means for rotating said shaft, and a musical device comprising a cylindrical member surrounding and spaced from said shaft, a series of sound emitting elements on said cylindrical member, a striker on said shaft, and means for vertically oscillating said cylindrical member, said last named means comprising a lever connected to said member, a rotary cam having an operative connection with said lever, and gear connections between said cam and said vertical shaft, said gear connections comprising gears having a fractional size ratio with respect to one another.

In testimony whereof I have affixed my signature.

FELIX LUNAR LOPEZ.
